UNITED STATES PATENT OFFICE.

JOHN S. TAYLOR, OF WILMINGTON, DELAWARE, ASSIGNOR TO E. I. DU PONT DE NEMOURS AND COMPANY, OF WILMINGTON, DELAWARE, A CORPORATION OF DELAWARE.

CLOSURE.

Application filed March 16, 1918. Serial No. 222,848.

To all whom it may concern:

Be it known that I, JOHN S. TAYLOR, of Wilmington, in the county of New Castle and in the State of Delaware, have invented a certain new and useful Improvement in Closures, and do hereby declare that the following is a full, clear, and exact description thereof.

My invention relates particularly to a device designed to act as a closure for boxes or cans of various different types, although it has application especially to boxes for shipping explosive powder of various kinds.

The object of my invention is to provide a closure which is so arranged that it may be manufactured in large quantities without difficulty and which is, furthermore, of such a nature and construction that it will effectively close the can or box to which it is applied, and which is of such a character, furthermore, as to be locked in place when once moved into closed position.

A further object is to provide a construction of this character which may be made at a comparatively low cost.

A further object is to provide a flexible and positive seal for boxes or cans and in which the pressure of the closure may be regulated to suit the conditions.

Further objects of my invention will appear from the detailed description thereof contained hereinafter.

While my invention is capable of embodiment in many different forms, for the purpose of illustration I have shown only one form thereof in the accompanying drawings, in which—

Figure 1 is a vertical section of the closure, enlarged;

Figure 2 is a plan view of the closure, enlarged;

Figure 3 is a plan view of the neck;

Figure 4 is a vertical section of the neck;

Figure 5 is a plan view of the cover;

Figure 6 is a section of the cover;

Figure 7 is a plan view of the spider;

Figure 8 is a section of the spider;

Figure 9 is a section of the screwthreaded ring applied to the spider;

Figure 10 is a section of the spider shown in Figure 7 and taken on line 13—13;

Figure 11 is a similar section thereof taken on line 14—14 of Fig. 7; and

Figure 12 is an elevation of the screw applied to the spider.

In the drawings I have shown a portion of a box or can having a sheet metal inner lining 1 located within a wooden outer casing 2. The lining 1 may be made of zinc or any other suitable metal, and may be made in one or more portions, and with any number of desired seams, by soldering or otherwise. In the top of the lining 1 there is an annular steel neck 3, which has an inner flange 4, adapted to be secured to the inside of the lining 1 by solder or otherwise. The neck 3 is provided outside of the wooden casing 2 with an enlargement 5 comprising an upwardly-directed rib 6 to engage and provide a seat for an annular rubber gasket 7. The gasket extends beyond the rib 6 into a depression 8, so as to lie within an outer wall 9 on the neck 3, which wall 9 leads to three laterally extending downwardly-curved flanges 10 on said neck 3, each of which has a notch 10^a therein. Upon its upper surface the gasket 7 is designed to be pressed downwardly by a downwardly-directed rib 11 on a cover 12, said cover having an upwardly-directed concave flanged portion 13 connected to a vertical wall 14, which forms, with an inner flat portion 15, a downwardly-directed extension fitting within the neck 3. The inner flat portion 15 has a number of radially-directed ribs 16, and is provided at its central point with a curved depression 17 to receive the inner end of a screw 18, which has a head 19, carrying a perforation 20 to receive a wire-and-lead seal of the usual type. The screw 18 is carried by a screw-threaded ring 21 secured to a spider 22, having three arms 23, each of which has at its outer end a downwardly and upwardly-directed tongue 24, to fit over the downwardly-curved flanges 10 on the neck 3, and in such a way that upwardly-directed projections 25 on the arms 23 interlock with

the notches 10^a thereon. The said spider 22, furthermore, has between the arms 23 downwardly-directed flanges 26, to strengthen the same. Again, one of the arms 23 is provided with an upwardly-directed transverse strap 27 to receive the wire-and-lead seal, which passes also through the perforation 20 in the screw 18.

In the operation of my invention, the can 10 or box having been constructed by flanging over the neck 3 so as to form the flange 4 on the inside of the inner lining thereof 1 and soldering or otherwise securing the flange to the lining 1, after the contents of the can 15 or box have been introduced into the same, the rubber gasket 7 is applied over the rib 6 and the cover is applied in such a manner that the downwardly-directed extension thereon passes into the neck 3, thus applying 20 the rib thereon to the upper surface of the gasket 7. Thereupon the spider 22 is applied by introducing the arms 23 between the downwardly-curved flanges and rotating the same until the projections 25 on the 25 arms 23 register with the notches 10^a on said projections. The screw 18 is then introduced into the ring 21 and screwed down, thus bringing about a compression of the gasket 7 between the ribs 6 and 11 and thus tightly 30 closing the can or box.

It will be noted that, once the screw 18 has been screwed down, the spider 22 cannot become loosened accidentally, as said spider is locked in place, due to the engagement of 35 the projections 25 with the notches 10^a. The wire-and-lead seal may be then applied by passing the same through the perforation 20 and under the strap 27. The closure of the can or box is then in such a position as not 40 only to prevent the passage of the gases and liquids through the neck 3, but said closure is effectively locked in place, so as to remain indefinitely in this position until it is desired to open the can or box.

45 While I have described my invention above in detail, I wish it to be understood that many changes may be made therein without departing from the spirit of the invention.

50 I claim:

1. A closure comprising a neck having an inner flange adapted to underlie the walls of an opening, an outer flange adapted to overlie such walls and provide a seat, and laterally-extending flanges overlying said seat, a spider adapted to engage under said laterally-extending flanges, a cover located between said spider and said neck, and means on said spider for forcing said cover toward 55 said seat.

60 2. A closure comprising an annular neck adapted to be received within an opening, said neck having at its upper end an annular seat adapted to rest on the walls of the open-

65 ing, the metal above said seat being shaped to provide an annular upwardly-extending outer wall surrounding said seat and flanges extending laterally therefrom above the seat, a spider having an edge adapted to engage under said flanges, a sheet-metal cover between said spider and said neck having an annular flange adapted to co-operate with said seat, and means on said spider for 70 forcing said cover towards said seat.

3. A closure comprising an annular neck 75 adapted to be received within an opening, said neck having at its upper end an annular seat adapted to rest on the walls of the opening, the metal above said seat being shaped to provide an annular upwardly-extending outer wall and lateral flanges extending outwardly therefrom, a spider having edges turned over and directed inwardly to engage under said flanges, a cover between said spider and said neck and means 80 on said spider for forcing said cover towards said seat.

4. A closure comprising a neck portion having an annular seat adapted to rest upon the exterior walls of an opening, a cover 90 having an outer rim adapted to overlie said seat, a spider overlying said cover, and means acting between said spider and said neck portion for forcing the rim of said cover toward said seat.

95 5. A closure comprising a neck portion having an annular seat adapted to rest upon the exterior walls of an opening, a cover having a central portion fitting within said neck portion and an outer rim adapted to 100 overlie said seat, a spider overlying said cover, means for interlocking said spider with said neck portion, and a device upon said spider for forcing the rim of said cover toward said seat.

105 6. A closure comprising an annular neck of sheet-metal adapted to be received within an opening, said neck having at its upper end an annular seat adapted to rest on the walls of the opening, the metal above 110 said seat being shaped to provide an annular upwardly-extending outer wall and flanges extending laterally therefrom, a spider having an edge adapted to engage under said flanges, said edge and flanges being provided 115 with a co-operating projection and recess to prevent rotation of the spider when in operative position, a cover between said spider and said neck and means on said spider for forcing said cover towards said seat.

120 7. A closure comprising an annular neck adapted to be received within an opening, said neck having at its upper end an annular seat adapted to rest on the walls of the opening, the metal above said seat being shaped to provide an annular upwardly-extending outer wall and flanges extending laterally therefrom, a gasket disposed on

said seat and having its outer side resting against said outer wall, a spider having an edge adapted to engage under said flanges, a cover between said spider and said neck, said cover having an annular flange adapted to rest on said gasket, and a vertical wall engaging the inner side of the gasket, whereby the gasket is confined between the vertical wall of the cover and the aforesaid

outer wall, and means on said spider for forcing said cover towards said seat.

In testimony that I claim the foregoing I have hereunto set my hand.

JOHN S. TAYLOR.
